ABSTRACT OF THE DISCLOSURE

A solid fuel gas generator such as a rocket engine includes a combustion chamber which is closed at one side by a cover containing a detonating cap and has an opposite closed side with a primer charge thereby. A main charge in a form of an annular burner is mounted between the detonator cap and the primer charge, and a throttle ring is interposed between one end of the charge and the detonator cap and it defines passages for the outflow of generated gases produced by the igniting gases and the burning of the interior of the main charge. The throttle ring permits gas to pass through a screen defined by one end of the cover which covers the detonating cap. The throttling action ensures that all of the gases which are generated in, or delivered to, the hollow interior of the main charge do not pass directly outwardly through the combustion chamber discharge but a portion proceeds along and around the opposite end of the main charge to inflame the exterior wall of the main charge and to maintain it ignited.

SUMMARY OF THE INVENTION

This invention relates, in general, to a method and apparatus for generating gases, and in particular, to a new and useful device and method for the uniform ignition of both the inner and outer jacket of a solid rocket composition formed as a tubular burner in a combustion chamber such as in a rocket engine.

In solid rocket engines, it is generally known to use tubular rocket compositions and to ignite them by means of one or more priming charges arranged in the combustion chamber head, the igniting charge being, in turn, ignited by detonator caps. The ignition of solid rocket compositions generally present some difficulties particularly for small engines, or engines which must work at very low ambient temperatures. Special problems arise with the use of tubular burners because it is difficult to provide a satisfactory ignition of the outer jacket of the burner after the inner jacket is ignited, because the outer jacket does not come into a sufficient contact with the generated gases during and after ignition of the priming charge thus follow the path of least resistance and flow resistance produced by the relatively narrow gap which is provided between the exterior of the main charge and the surrounding combustion chamber wall is substantially greater than the flow resistance through the interior of the charge to the discharge of the combustion chamber. The ignition gases which are produced by the priming charge thus allow the path of least resistance and flow primarily through the interior of the rocket composition directly to the combustion chamber outlet. The small amount of ignition gases which do flow through the narrow outer annular slot of the exterior of the solid charge cools off very rapidly due to the great heat transfer to the combustion chamber wall which forms a large surface having a greater density than the charge itself.

2

This results in a great disadvantage in that it provides a great ignition delay and a poor consumption efficiency and reduces the specific impulse of the generated gases. In many cases, the ignition temperatures for kindling the combustion in the range of the outer jacket of the tubular burner is not achieved at all. This can result in a pressure drop below the critical value necessary for the operation of the combustion chamber and may result in the complete extinction of the main charge. For these reasons, 5 the use of tubular burners is frequently forgone particularly for small rocket engines and in solid engines which must work under the above-mentioned conditions. This is true even though they might otherwise have certain advantages in terms of combustion characteristics and 10 when a more expensive outer insulation can be forgone without risk but with the use of front and pure inner burners.

In order to avoid the difficulties of the prior art, the present invention provides a tubular burner which is arranged within a combustion chamber in a manner such that the central area of the burner may be ignited by the detonating charge and the primer charge and the gases which are generated are directed to flow outwardly from both ends of the tubular burner, one gas flow being 15 directed around the exterior of the main charge to maintain the ignition of the exterior and the other gas flow being directed outwardly through the engine discharge. The arrangement ensures satisfactory ignition even of the outer jacket of the tubular burner and provides a means 20 for burning the whole charge uniformly throughout its entire burning cycle.

In order to ensure that a portion of the gases which are generated by the initial ignition of the interior of the charge and the primer charge gases are used to ignite 25 the exterior wall of the main charge, the invention provides an arrangement of a throttling between the detonator and the charge in the path of the flow of the gases to the outlet of the combustion chamber. The throttling increases the amount of pressure acting on this gas flow 30 so that a portion will be diverted backwardly through the opposite end of the charge where it is then directed around the exterior wall of the charge to ignite and maintain ignition of this outer wall. The throttling may be maintained over the entire combustion period with 35 rocket compositions having very short combustion periods, for example, of only a few thousands or hundreds of a second. However, with engines of relatively long combustion periods, for example, of several seconds or minutes, the throttling is effected only during the ignition phase, that is, during the combustion of the priming charge and during the initial phase of the combustion of 40 the rocket composition.

According to a method of the invention, the throttling 45 of the gas current produced by the igniting of the interior of the main charge, is effected only during a predetermined operating period which is sufficient to positively ignite the outer wall of the charge and to keep the combustion going. This length of time will depend particularly on the type and size of the combustion chamber and 50 on the environmental condition such as temperature and pressure. As a specific solution, it is suggested that a throttling element may be provided between one end of the main charge and the discharge of the combustion chamber. The throttling element may be of a combustible material or of a fusible material (such as plastic). Such a material should have a combustion or melting time which corresponds to the ignition time of the outer jacket of the tubular burner. With such an arrangement, it is 55 possible to progressively reduce the throttling effect of the priming charge and of the rocket composition of the main charge during the combustion of the main charge 60 65 70

by using a substance for the throttling element which has the same or higher combustion rate than the rocket composition of the main charge.

It is also possible to construct the throttling element as a ring having an opening or flow window which is arranged around the one end of the main charge and which has a mean diameter corresponding to the mean diameter of the hollow cylindrical main charge. Such a ring may be formed of steel or other incombustible material so that it provides a constant throttling over the entire combustion period of the main charge.

The throttling of the gases generated by the burning of the interior of the main charge may be controlled in dependence on the temperature on the gas current which is passed around the exterior of the charge in a manner such that the throttling is progressively reduced, or completely stopped, when a temperature is attained which ensures the further combustion on the outer wall of the main charge. To achieve this, the throttle ring is made of a combustible material and covered over its surface with a noncombustible insulating coat so that it will not be ignited by the flow of the generated gases thereby until a temperature sufficiently high enough to penetrate the insulating coating is attained. The ignition may be achieved by the arrangement of the ignitable temperature feeler which is connected to the combustible material of the throttle through an ignition wire which is insulated on its surface. The wire will ignite when the temperature has been reached which is sufficient to ensure the ignition of the outer jacket and the maintenance of this ignition. When this occurs, the throttling is ignited and the burning consumes the ring so that the ring is destroyed and the throttling effect is reduced.

A particular advantage of the invention is that a wider field of application of the tubular burner is possible since a maximum combustion surface and favorable combustion tendencies and combustion efficiencies are attainable. A principal advantage of the tubular burner is that its combustion rate can remain relatively low and a less expensive and less sensitive powder can be employed for the main charge and in addition, the development risks for such a construction are very low.

Accordingly, it is an object of the invention to provide a method of igniting and burning a hollow charge in a combustion chamber or other gas producing device which comprises igniting the central portion thereof and throttling the gases which are generated in their passage to the discharge of the combustion chamber so as to cause the flow of a portion of these gases around the opposite end of the charge and the exterior wall of the charge in order to ignite and maintain the ignition of the exterior wall at least for a portion of combustion period.

A further object of the invention is to provide a device for generating thrust gases which includes a hollow solid charge mounted with one end adjacent a detonator and another end adjacent a primer charge and with throttling means adjacent the detonator end in the path of flow from the interior of the hollow charge to the outlet of the combustion chamber and providing a throttling effect to divert a portion of the gases from the interior of the charge around the exterior wall of the charge before exiting through the outlet of the combustion chamber.

A further object of the invention is to provide a combustion chamber construction which includes a throttling member disposed between the flow path of gases from the interior of a tubular charge to the outlet of the combustion chamber, the throttling member being located to require a portion of the gases to pass around the exterior wall of the hollow charge and being made of a material, such as steel which provides a uniform throttling effect during the entire combustion period or a consumable material which may be partially or completely consumed so as to reduce the throttling effect as combustion progresses.

A further object of the invention is to provide a gas generating device which is simple in design, rugged in construction and economical to manufacture.

The various features of novelty which characterize the invention are pointed out with particularity in the claims annexed to and forming a part of this specification. For a better understanding of the invention, its operating advantages and specific objects attained by its use, reference should be had to the accompanying drawings and descriptive matter in which there are illustrated and described preferred embodiments of the invention.

In the drawings:

FIG. 1 is a partial transverse sectional view of a portion of a rocket engine combustion chamber constructed in accordance with the invention; and

FIG. 2 is an enlarged partial sectional view similar to FIG. 1 but showing another embodiment of the throttling device.

Referring to the drawings, in particular, the invention embodied therein in FIG. 1 comprises a gas generating device such as a rocket engine which includes a combustion chamber 1 in which is located a solid rocket composition or main charge 2. The main charge 2 is of hollow cylindrical construction and it is centered within the combustion chamber by means of a centering and holding device 3. A flow passage 14 is defined between the interior walls 13 of the combustion chamber and the exterior wall of the main charge 2. A priming charge 4 is disposed adjacent the inner end of the hollow main charge 2 and is slightly spaced therefrom or includes passages to provide a flowpath through this end over or through the priming charge 4 and through one or more passages defined in the holding device 3.

The combustion chamber 1 includes an opposite end 35 which is closed by a cover member or housing 6 which carries a detonating charge or detonator cap 5. The housing 6 includes an elongated tubular extension having an outwardly extending flange 10 which forms a flow screen having a plurality of bores 10a therethrough. The tubular end of the housing 6 engages around throttle means including a throttle ring generally designated 7 and positions this ring between the detonating cap and the end of the hollow charge 2 adjacent a discharge or outlet 12 of the combustion chamber.

In accordance with the invention, the throttle means are located at the end of the main charge 2 which is adjacent a gas discharge or outlet 12. The throttle means throttles the gas flow, which flows from the interior of the charge directly to the outlet 12 and produces at least a partial backflow in the interior of the charge and around the exterior thereof the throttle ring 7 includes a hub portion 8 which bears against the interior of the tubular extension of the housing 6 so that the throttle ring 7 is accurately positioned against the end wall of the solid charge 2. An insulation layer may advantageously be formed between the end of the main charge 2 and the throttle ring 7. The throttle ring 7 has a plurality of circumferentially spaced ports or openings 9 which permits flow from the interior J of the solid charge 2 through the ports 9, the openings 10a of the screen 10, and out the outlet 12.

The throttle ring 7 has a mean diameter d which is equal to, or about equal to, the mean diameter D of the main charge 2. Insulation of the end of the hollow charge 2 adjacent the rocket ring prevents combustion or wearing away of the ring at this location, and ensures that the throttling effect will be maintained. The housing 6 defines an annular flow space 11 between the screen or flange 10 and the outer portion of the housing 6. This annular space 11 communicates with the outlet 12.

The method of operation of the device is as follows:

The detonator cap 5 is ignited and the ignition jet penetrates through the interior J of the solid charge 2 and impinges on the priming charge 4 which is thus ignited. The ignition of the priming charge 4 as well as the ignition of the entire length 15 of the interior of the solid charge

2 causes the generation of gases. A portion of the priming charge gases will flow in the form of an inner current which will move upwardly in the direction of the arrows designated Z_i and another portion Z_a will flow upwardly in the annular passage 14. After ignition of wall 15, gases as indicated by the arrows G_i will flow upwardly from the burning of the charge 2 and, as indicated by the arrows G_a around the bottom end of charge 2 and upwardly along the side wall 16. Because of the throttling effect produced by the ring 7 only a portion of the gases which are generated during ignition and burning of the main charge 2 will flow upwardly in the currents Z_i and G_i , and pass through the openings 9, the screen openings 10a and into the annular space 11 for discharge through the outlet 12. A remaining portion will flow in the streams Z_a and G_a downwardly over the priming charge 4 and then upwardly through the passages defined in the holding device 3 in the passageway 14 in order to contact the exterior wall 16 of the solid charge 2.

The throttle 7 thus insures that the gases which are formed initially within the interior space J of the main charge 2 do not all flow through this end of the charge out the outlet 12, but that a portion of them flows around the exterior of the solid charge to maintain an ignition temperature along the exterior wall 16 during the combustion period.

As indicated in FIG. 2, a throttle ring 17 which is made of combustible material may be employed instead of the ring 7 which is made of a material such as steel. In this instance, the entire surface of the throttle ring 17 is covered with a noncombustible insulating coat 18 so that it cannot be ignited by the inner partial gas current Z_i and G_i which will flow therearound. A combustible substance within the throttle ring 17 is engaged by an ignition wire 19 which is insulated with a noncombustible fire retarding coat and it extends into the annular slot 14. At the end of the ignition wire 15, there is arranged an ignitable temperature feeler 20. When a temperature of the outer gas current G_i which moves over the exterior wall of the main charge is attained which will ensure that the outer jacket or wall 16 will be ignited and maintained burning, the temperature feeler 2 will ignite to set the combustible substance in the throttle ring 17 afire and to cause the burning of the ring until it is completely consumed and no longer provides a throttling effect on the main charge. This produces a direct outflow of all of the propellant gases produced by the combustion of the main charge 2 from both the interior and the exterior thereof. It is desirable that the throttling effect be reduced as rapidly as possible in order to avoid any unnecessary flow losses around the annular slot 14.

The flow screen 10 serves to retain any solid pieces which are detached from the rocket composition 2 until they are completely burnt in order to avoid that a device which is operated by the gases which are generated will not be adversely affected. For example, a mechanically sensitive gas turbine would be damaged by the carry over of large pieces of the main charge. In addition, the flow screen 10 ensures the lowering of the high temperature of the propellant gases by the heat withdrawal down to an operating temperature admissible for a subsequent device such as a turbine. In addition, soot and other impurities will be deposited on the screen to apply the cooling effect which it produces.

What is claimed is:

1. A method of operating a thrust gas generator such as a rocket engine having a hollow substantially cylindrical charge arranged in a combustion chamber which has an outlet adjacent one end of the charge, comprising igniting the interior of the charge and throttling the interior of the end of the charge adjacent the outlet of the combustion chamber while permitting at least a partial gas flow through the opposite end and around the opposite end of the charge past the exterior wall thereof to ignite

and to aid in maintaining ignition of the exterior wall of the charge.

2. A method, according to claim 1, wherein the solid charge employed has a relatively long combustion time, comprising throttling of the end of the charge adjacent the outlet of the combustion chamber only during the ignition phase and initial stages of combustion of the charge.

3. A method, according to claim 1, wherein the throttling of the charge at the end adjacent the outlet of the combustion chamber is effected only during a predetermined period which corresponds to the time required for igniting the exterior of the main charge.

4. A method, according to claim 1, wherein the throttling is progressively reduced.

5. A device for generating gases such as thrust gases for a rocket engine comprising wall means defining a combustion chamber having an outlet, a hollow tubular charge having a burnable interior and exterior and being located within said combustion chamber and having a first end adjacent the combustion chamber outlet and an opposite second end, said charge being spaced inwardly from said wall means and defining an exterior flow passage around the exterior of said charge communicating with said second end, and throttle means at said first end located to throttle the gas flow from the interior through said first end and through said outlet and producing at least a partial flow of gases from the interior of said charge around said second end and through said exterior flow passage in contact with the exterior wall of said charge, and means for igniting the interior of said tubular charge.

6. A device, according to claim 5, wherein said throttle means includes a ring extending around the opened interior of said tubular charge and abutting against said first end, said ring having a plurality of flow ports therethrough communicating on one side with the interior of said tubular charge and on the opposite side with the outlet of said combustion chamber.

7. A device, according to claim 6, including a cover member for positioning a detonation cap adjacent first end of said charge engaged with said ring and holding said ring in position adjacent said first end of said charge, the mean diameter of said ring corresponding approximately to the mean diameter of said hollow charge.

8. A device, according to claim 5, wherein said throttle means comprises a consumable throttle member.

9. A device, according to claim 8, wherein said throttle member is made of combustible material.

10. A combustion chamber construction comprising wall means defining an interior combustion chamber having an outlet, a hollow tubular charge having a first end located adjacent the combustion chamber outlet and an opposite second end remote from the outlet, means mounting said tubular charge within said combustion chamber at a location to define an annular flow passage around the exterior of said charge, means holding a detonation cap at a spaced location from said first end of said charge, a throttle ring disposed between said holding means and said first end of said charge and having at least one opening therethrough permitting flow from said first end of said interior of said charge into said ring and through the opening to said outlet, a priming charge arranged adjacent said second end of said hollow charge, the throttle member being such to ensure a partial flow of gases produced after ignition from the interior of said hollow charge toward first end for passage through the opening of said throttle member to said outlet and also from the interior of said charge to said second end around the exterior wall of said charge for ignition of the exterior wall and flow outwardly to said outlet.

11. A device, according to claim 10, wherein said means for holding said ring adjacent said first end of said hollow charge includes a flange member extending outwardly from said holding means and defining a screen, said screen being located between said outlet and the flow

passed from the openings of said ring and from around the exterior of said hollow charge to said outlet.

12. A device, according to claim 11, wherein said hollow charge is insulated from said ring.

13. A device, according to claim 10, wherein said throttle ring is made of a combustible material, and on igniting wire extending into said combustible material and having a feeler portion which is ignitable upon reaching of a predetermined temperature and which is located within the annular passage around the exterior of said hollow charge.

14. A device, according to claim 10, including a detonation cap held by said means for holding said detonation cap and located in alignment with the first end of said tubular charge but on the opposite side of said throttle ring.

15. A device, according to claim 14, wherein said holding means engages said ring and positions said ring adjacent the first end of said hollow charge said holding means including a outwardly extending flange surrounding said ring and located between the openings of said ring and said outlet.

16. A method of operating a thrust gas generator, such as a rocket engine, having a hollow substantially cylindrical charge arranged in a combustion chamber which has an outlet adjacent one end of the charge, comprising igniting the interior of the charge and throttling the end of the charge adjacent the outlet of the combustion chamber to produce at least a partial gas flow through the opposite end and around the opposite end of the charge past the exterior wall thereof to ignite and to aid in maintaining ignition of the exterior wall of the charge, the throttling being controlled in dependence on the tem-

perature of the gases which are directed around the exterior of the main charge.

17. A method of operating a thrust gas generator such as a rocket engine having a hollow substantially cylindrical charge arranged in a combustion chamber which has an outlet adjacent one end of the charge, and wherein the throttling element is made of a combustible material comprising igniting the interior of the charge and throttling the end of the charge adjacent the outlet of the combustion chamber to produce at least a partial gas flow through the opposite end and around the opposite end of the charge past the exterior wall thereof to ignite and to aid in maintaining ignition of the exterior wall of the charge and igniting the combustible throttling material after the temperature of the exterior of the hollow charge has reached a predetermined amount so as to reduce and substantially eliminate the throttling effect thereof.
